United States Patent Office

Des. 176,993
Patented Feb. 28, 1956

176,993

COFFEE SERVER STAND

Daniel C. O'Connell, Bedford Village, N. Y., assignor to Sterno, Inc., New York, N. Y., a corporation of New York

Application December 2, 1954, Serial No. 33,372

Term of patent 14 years

(Cl. D81—10)

Fig. 3

Fig. 2

Fig. 1 is a top plan view of the coffee server stand embodying my new design;

Fig. 2 is an elevational view thereof; and

Fig. 3 is a perspective view of the coffee server stand. I claim:

The ornamental design for a coffee server stand, as shown.
